[57] ABSTRACT

A tube progressively decreases in sectional area from an inlet to an outlet while spiraling outwardly. The tube is affixed within a bell rotatable on a housing which has an intake chamber adjacent the tube inlet. A shaft journaled on the housing drives the bell. The slope of the tube relative to an axial plane through the shaft progressively increases from inlet to outlet. The outlet opens into an annular passageway defined by the bell and housing and having a discharge opening for pumped fluid.

CENTRIFUGAL PUMP STRUCTURE

This invention relates to a centrifugal pump. The conventional centrifugal pump comprises a shaft with generally radial impeller blades mounted thereon, the shaft being rotatably mounted on a housing so that the blades turn within a chamber in the housing. The fluid to be pumped is drawn axially inwardly through a generally central inlet and is forced radially outwardly to an outlet by the impeller blades. This results in an abrupt change of direction of the fluid being pumped and a consequent loss of efficiency. In addition, when the pumped fluid is a liquid, the abrupt change of direction tends to cause cavitation resulting in further inefficiency.

The object of the present invention is to provide a relatively simple pump structure improved to eliminate the above-mentioned inefficiencies and further improved to increase efficiency by controlling the direction of flow of the fluid discharging from the pump. One form of the invention is shown in the accompanying drawings.

FIG. 1 is a partly diagrammatic view of a pump according to the invention shown partly in section and partly in elevation.

FIG. 2 is a sectional view on line 2—2 of FIG. 1.

FIG. 3 is a sectional view on line 3—3 of FIG. 1.

Shown in the drawings is a pump 10 according to the invention having a body 12 which includes a base 14, a housing 16, and a cap 18. Base 14 and housing 16 are secured together by suitable means such as flanges 20 and 22 respectively thereon anchored to each other by bolting (not shown). Similarly, cap 18 is secured to housing 16 by suitable means such as flanges 24 and 26 respectively thereon anchored to each other by bolting (not shown). Pump 10 may be supported on a mount 28 by engaging base flange 20 on the mount.

Base 14 has an intake pipe 30 adapted for connection to a pipe or hose 32 which extends to a source of fluid to be pumped. Intake pipe 30 opens into an intake chamber 34 in base 14. A generally bell-shaped rotor 36 has a small end 38 rotatably supported by a shoulder 40 on base 14 through an interposed bearing structure 42. Rotor 36 has a larger end 44 spaced radially inwardly of a skirt 46 on cap 18. Large end 44 is provided with a closure 48 slightly spaced from cap 18 as at 50.

Rotor 36 is driven by a shaft 52 journaled on base 14 at 54 on cap 18 at 56. A suitable drive connection is provided between shaft 52 and rotor 36 which may comprise, for example, a spline connection 58 between the shaft and a central hub 60 on closure 50. Shaft 52 extends centrally through rotor 36 and its smaller end 38 and through intake chamber 34. O-ring seals 62, 63 and 64 are provided between the shaft and base 14, hub 60 and cap 18 respectively. A seal 65 is provided adjacent the juncture of small end 38 of rotor 36, housing 16 and bearing structure 42. Shaft 52 is driven by suitable means such as a belt 66 entrained around a pulley 68 thereon and around the output pulley of a motor.

At least one impeller tube 70 is mounted within rotor 36. Tube 70 has an upstream end portion 72 affixed to the smaller end 38 of rotor 36 and has a downstream end portion 74 affixed to a generally axially extending portion 76 of rotor 36 adjacent larger end 44. Upstream end portion 72 defines an inlet 78 and downstream end portion 74 defines an outlet 80. Inlet 78

opens into intake chamber 34 and outlet 80 opens into an annular chamber 82 defined by housing flange 24, cap skirt 46, and portions 44, 76 of rotor 36. Chamber 82 is provided with a discharge pipe 84 for the pumped fluid. Except for inlet 78 and outlet 80 the ends of rotor 36 are isolated from chambers 34 and 82 by suitable seals to prevent pumped fluid from entering the rotor outside of tube 70.

Tube 70 has the general shape of a spiral between its inlet 78 and outlet 80. Upstream end portion 72 is located radially closely adjacent shaft 52. Progressing angularly and axially downstream from the inlet the following variations in the tube occur: the radial distance of the tube from the shaft progressively increases to a maximum at outlet 80; the slope of the tube relative to an axial plane through shaft 52 progressively increases to a maximum at outlet 80; and the effective sectional area of the tube progressively decreases, preferably uniformly, to a minimum at outlet 80.

Tube 70 turns through an angle of at least 180° between inlet 78 and outlet 80. The slope of the tube at outlet 80 relative to an axial plane through shaft 52 is preferably in the range from about 70° to about 90°. The axis of the tube at outlet 80 is disposed rearwardly with respect to the direction of rotation of rotor 36 for a purpose to be described. The radially outer surface portions of tube 70 are engaged against the interior surface of the wall defined by bell-shaped rotor 36.

In use, let it be assumed that pump 10 has been primed by filling pipe 32, intake pipe 30, intake chamber 34, and tube 70 with the fluid to be pumped to a level slightly above inlet 78. The motor connected with belt 66 is set into operation for rotating pulley 68, shaft 52, and rotor 36 together with tube 70 in a clockwise direction as the drawings are viewed. Because of the slope of lower portion 72 of the tube the fluid is forced outwardly and axially away from inlet 78 by centrifugal force, which force progressively increases as the fluid moves downstream because of the progressively increasing radial distance of the tube from shaft 52. The centrifugal force reaches its maximum adjacent outlet 80.

The body of water moving within the tube gradually changes direction because of the progressive change in slope of the tube and at outlet 80 the fluid flows at an abrupt angle to an axial plane through shaft 52 as best seen in FIG. 1. Also, the velocity of flow of the fluid in the tube increases to a maximum at outlet 80 because of the progressively diminishing sectional area of the tube. The fluid is discharged into annular ring 82 and then through discharge pipe 84 at high kinetic energy. Since the fluid is forced out of outlet 80 in a direction generally opposite to the direction of rotation of rotor 36, the reaction thereto assists rather than resisting the motor effort of rotation of the rotor.

The gradual change of direction of the flowing body of fluid, the gradual increase of centrifugal force thereon, and the gradual acceleration of the fluid in passing through tube 70 decreases the tendency toward cavitation of pumped liquid and together with the propulsion effect of the water exiting from outlet 80 contributes to overall efficiency of the pump.

The wall of rotor 36 supports tube 70 against the centrifugal force exerted thereon.

For purposes of clarity and simplicity of illustration pump 10 has been illustrated as having only one tube 70. Such a pump would operate satisfactorily though it

might vibrate to a certain extent. It is contemplated that in commercial usages of the present invention pump 10 will incorporate a plurality, say two or three, tubes 70 mounted within bell-shaped rotor 36 symmetrically about the axis of shaft 52. Such a structure has the advantages of multiplied output plus a tendency to cancel possible vibrations in the structure.

In the drawings rotor 36 and tube 70 are represented as comprising a single integral body. An experimental working model of pump 10 in fact has this structure. However, in commercial models bell 36 and tube 70 will likely comprise separate elements secured together at appropriate locations such as adjacent inlet 78 and outlet 80 by bolting or the equivalent and the use of fluid tight seals where required.

It is believed that a typical commercial pump 10 according to this invention will have three tubes 70 each with an inlet 78 diameter of about 4½ inches, an outlet 80 diameter of about one inch, the radial distance from the axis of shaft 52 to the neutral axes respectively of inlet 70 and outlet 80 being about 4½ inches and 12 inches, the axial length of tube 70 being about 19 inches, the tube turning through about 360° and varying in slope relative to an axial plane through shaft 52 from about 50° to about 90°. By way of example, according to my calculations a pump 10 so constructed can be turned at 5,000 rpm by a 5 horse power motor and at that rate of operation will pump theoretically as much as 5,600 gallons of water per minute, or taking into consideration resistance factors not yet determined through experimentation, about 2,800 gallons per minute. The pump can be produced in different sizes to meet various capacity requirements.

I claim:

1. Centrifugal pump structure which comprises, a body, a shaft rotatably mounted on said body, a tube, and means forming a driving connection through which said tube is rotated by said shaft, said body having a chamber adapted to receive fluid to be pumped, said tube having an inlet adjacent one end open to said chamber, said inlet having a relatively large effective area and being located relatively closely to said shaft, said tube having an outlet adjacent its other end which is spaced from said inlet in a direction axial of said shaft, said outlet having a relatively small effective area and being located radially farther from said shaft than said inlet, said tube, progressing from said inlet toward said outlet, having an effective sectional area which progressively decreases, having a slope relative to an axial plane through said shaft which progressively increases, and having a radial distance from said shaft which progressively increases.
2. The structure defined in claim 1 wherein said tube has the general shape of a spiral which, progressing from said inlet toward said outlet, turns in a direction opposite to its direction of rotation by said shaft.

3. The structure defined in claim 2 wherein said spiral turns through at least 180°, said slope adjacent said outlet being in the range of about 70° to about 90°.
4. The structure defined in claim 3 wherein said spiral turns through about 360°, said slope adjacent said outlet being about 90°.
5. The structure defined in claim 3 wherein said outlet faces generally in said opposite direction.
6. The structure defined in claim 1 wherein said driving connection comprises a generally bell-shaped element mounted on said shaft for rotation therewith, said element having a wall with interior surface portions shaped complementally to exterior surface portions of said tube, said tube being affixed within said element with said surface portions interengaged.
- 10 7. The structure defined in claim 6 wherein said element supports said tube against centrifugal force exerted thereon incidental to operation of said pump structure.
8. The structure defined in claim 7 wherein said inlet opens generally longitudinally through a smaller end of said element into said chamber, said outlet opening laterally through a circumferentially extending portion of said wall adjacent the larger end of said element.
- 25 9. The structure defined in claim 8 wherein said element is rotatably supported on said body through a bearing with said smaller end adjacent said chamber.
10. The structure defined in claim 9 wherein said body defines a housing around said element, portions of said housing and element cooperating to define a closed hollow ring around said circumferentially extending portion of said wall into which pumped fluid discharges from said outlet, said ring having a discharge opening.
- 30 11. The structure defined in claim 10 wherein said cooperating portions of said body and element include a closure for the larger end of said element, a cap on said body overlying but spaced from said closure, said cap extending radially outwardly of said element and having an annular skirt spaced radially outwardly of said circumferentially extending portion of said wall.
- 40 12. The structure defined in claim 11 wherein said shaft is journaled on said cap, extends through said closure, element and chamber, and is journaled on said body adjacent said chamber.
13. The structure defined in claim 12 wherein said body, between said bearing and said ring, is shaped generally complementally to but spaced from said element.
- 50 14. The structure defined in claim 13 wherein a fluid-tight seal is provided between the smaller end of said element and said body.
15. The structure defined in claim 1 wherein a plurality of said tubes are symmetrically arranged around said shaft, each having a said driving connection therewith.
- 55 16. The structure defined in claim 1 wherein said sectional area decreases substantially uniformly.
